Seeman & Catron,

Clothes Frame,

No 61,473,

Patented Jan. 22, 1867.

United States Patent Office.

JOHN SEEMAN AND SILAS P. CATROW, OF MIDDLETOWN, OHIO.

Letters Patent No. 61,473, dated January 22, 1867.

IMPROVED CLOTHES-DRYER.

The Schedule referred to in these Letters Patent and making part of the same.

TO ALL WHOM IT MAY CONCERN:

Be it known that we, JOHN SEEMAN and SILAS P. CATROW, of Middletown, in the county of Butler, and State of Ohio, have invented a new and improved Clothes-Rack or Horse; and we do hereby declare that the following is a full, clear, and exact description thereof, which will enable others skilled in the art to make and use the same, reference being had to the accompanying drawings, forming part of this specification.

The present invention relates to a novel construction of a clothes-rack or horse, whereby, when not in use, it can be folded into a very compact shape; the rack, when opened for the hanging of clothes upon it, possessing many advantages, which will be hereinafter particularly described—

In the accompanying plate of drawings our improved clothes-rack or horse is illustrated—

Figure 1 being a perspective view of the same opened.

Figure 2, a similar view, closed; and

Figure 3, a perspective view in detail.

Similar letters of reference indicate like parts.

A, in the drawings, represents our improved clothes-rack or horse, which consists of two similar frames B, having cross-bars b, and hinged together at their upper ends so as to be opened from and closed upon each other, as is shown in the drawings, figs. 1 and 2, respectively, tie-cords h limiting the extent to which the two frames B can be opened from each other. E, two frames, hung to the upright frames B, one to each of the same, so as to swing thereon, which two frames E, when in a horizontal position, as plainly shown in fig. 1 of the drawings, are there secured or held by locking them together through their ends G, suitably notched to fit and lock into each other, the said frames E, when the clothes-rack is closed or shut up, being swung down and against the sides of the same upon opposite sides of the frames B. H, hooks or pins, secured in the end pieces of the horizontal frames E, which hooks are provided for the hanging of clothes upon them, such as skirts, dresses, etc., when the clothes-rack is opened.

Among the many advantages secured by our improved clothes-rack may be here mentioned as the most important, that, first, the rack, when closed or shut up, will be very compact in shape, taking up but very little space in a room, while, when opened for receiving clothes, it presents a large amount of hanging surface; second, a free circulation of air is secured about the clothes upon the horse; and third, the rack is simple, cheap, and durable in construction, thus rendering it one of the most desirable articles for household use.

We claim as new, and desire to secure by Letters Patent—

In combination with the hinged frames B, the frame E hung thereto and locking together, substantially as described for the purpose specified.

JOHN SEEMAN,
SILAS P. CATROW.
